COOF

Filed Nov. 27, 1928

UNITED STATES PATENT OFFICE

JOSE F. CARPENTER, OF BRIGHTWOOD, VIRGINIA

COOP

Application filed November 27, 1928. Serial No. 322,216.

This invention relates to coops designed primarily for enclosing or housing fowls, but it is to be understood that a coop in accordance with this invention may be employed for any purposes for which it is found applicable, and the invention has for its object to provide, in a manner as hereinafter set forth a structure of the class referred to including a door to enable entrance thereto and further with means permanently acting to maintain the door in closed position thereby preventing the accidental shifting of the door on its hinge to open position if the door is unlatched.

A further object of the invention is to provide, in a manner as hereinafter set forth, a structure of the class referred to including a hinged door and means to prevent the free movement thereof from closed position.

A further object of the invention is to provide, in a manner as hereinafter set forth, a structure of the class referred to including a door, a hinged rod for the latter and means to prevent the door, in case of warping from binding on the rod thereby permitting of the door to be easily swung and shifted to and from closed position.

A further object of the invention is to provide, in a manner as hereinafter set forth, a structure of the class referred to including a door opening, a door for closing and of less width than the width of the opening, a hinged rod for the door, a coiled controlling spring permanently acting to maintain the door in closed position, and with one of the walls of the door opening and the door having opposed sockets for the housing of the end portion of the spring thereby permitting of the employment of a spring of increased length and strength whereby the latter will be such as to prevent the free moving of the door on its hinged rod resulting in the door being normally maintained in closed position.

A further object of the invention is to provide, in a manner as hereinafter set forth, a coop structure including a slidably mounted hinged door so constructed and arranged as to enable it to be shifted the full width of the door opening of the coop and whereby a latch of materially increased length can be em-

ployed for entering the door transversely of the latter.

Further objects of the invention are to provide, in a manner as hereinafter set forth a coop structure which is simple in its construction and arrangement, strong, durable, compact, thoroughly efficient in its use, readily assembled, and comparatively inexpensive to manufacture.

With the foregoing and other objects in view the invention consists of the novel construction, combination and arrangement of parts as hereinafter more specifically described, and illustrated in the accompanying drawings wherein is shown an embodiment of the invention, but it is to be understood that changes, variations and modifications can be resorted to which fall within the scope of the claims hereunto appended.

In the drawings wherein like reference characters denote corresponding parts throughout the several views:

Figure 1 is a top plan view, partly in section of a coop in accordance with this invention.

Figure 2 is a fragmentary view taken on line 2—2 of Figure 1 of the top.

Figure 3 is a section taken on line 3—3 Figure 1.

Figure 4 is a fragmentary view in perspective of the crate.

Figure 5 is a fragmentary view in perspective illustrating the interlocking or interengaging of the slats.

Figure 6 is a plan view illustrating a modified form of door.

The coop includes a top frame formed of side members 1, 2, end members 3, 4, and spaced, lengthwise disposed combined bracing and supporting bars 5, 6 having their ends abutting against the inner faces of and secured to the end bars 3, 4.

The side members 1, 2 are formed with spaced, vertically disposed sockets 7 and spaced, horizontally disposed sockets 8. The sockets 7 open at the lower faces of said members 1, 2 and the sockets 8 open at the inner faces of members 1, 2. Each socket 7 in proximity to its upper end is intersected by a socket 8 adjacent the inner end of the latter. Each of the end members is pro-

vided with vertically disposed, spaced sockets 9. The bars 5, 6 are provided with horizontally disposed, spaced bores or openings 10, 11 respectively. The bores 10 are arranged in alignment with the bores 11 and with the horizontal sockets 8 in the member 1. The bores 10, 11 correspond in contour to horizontal slats to be presently referred to. The horizontal sockets 8 in the member 2 are arranged in alignment with the bores 11. There is a permanent tongue and groove connection between the frame members at the ends thereof and which is indicated at 12. Each corner of the frame is provided with a vertically disposed opening 13 for a purpose to be presently referred to.

The top of the coop is provided by the top frame bars 5 and 6 and four sets of slats. The slats are horizontally disposed and each slat 20 is in the form of a cylindrical rod. The slats of one set are indicated at 13, another set at 14, another set at 15 and the other set at 16. The set of slats 15 oppose the set of slats 16 in spaced relation.

25 One of the slats 13, has a portion thereof indicated at 17 providing a hinge rod for one end of a door to be presently referred to. One of the slats 16, has a portion thereof indicated at 18 providing a latch for the door 30 and one of the slats 14 has a portion thereof, as indicated at 19 providing an abutment for the non-hinged end of the door. The slats 13 are of the same length as the slats 14. The slats 15 are of less length than the 35 length of the slats 13, 14. The slats 16 correspond in length to the length of the slats 15 with the exception of that slat 16 which provides the latch 18 for the door and said slat is of greater length than the remainder 40 of the slats 16, as well as the slats 15, but of less length than slats 13, 14.

Each of the slats 13 in proximity to each end thereof and each of the slats 14 in proximity to each end thereof is formed with a 45 transverse groove 20 which when the slats are in position is disposed vertically. The outer end of each of the slats 15 and each of the slats 16 is formed with a transverse groove 21 which when said slats are in position are disposed vertically. The slats 13 have one end thereof anchored in the sockets 8 formed in the frame member 1 and the other ends thereof mounted in the sockets 8 formed in the frame member 2. The slats 55 14 have one end thereof mounted in the sockets 8 formed in the frame member 1 and the other ends thereof mounted in the sockets 8 formed in the frame member 2. The slats 15 and 16 are arranged between the slats 13 and 14 and said slats 15 have their outer ends arranged in the sockets 8 of the frame member 1 and their inner ends arranged in certain of the bores 10 formed in the bar 5. The slats 16 have their outer ends arranged in 60 sockets 8 formed in the frame member 2 and

their inner ends in certain of the bores 11 formed in bar 6. That slat having the latch 18 extends inwardly from the bar 6. The slats 13 and 14 extend through certain of the opposed bores 10, 11 formed in the bars 5, 6. 70

The top of the coop is formed with a door opening 22 having a pair of opposed walls thereof provided by opposed portions 23 of the bars 5, 6, another wall thereof provided by the hinge rod 17 and the remaining wall 75 thereof by the abutment 19. The latch 18 projects into the door opening 22. The bar 5 is formed with a horizontally disposed socket 24 which opens at the inner side face of bar 5 at the hinge rod 17. 80

The door for closing the opening 22 consists of a rectangular body portion 25 provided at one end with a horizontally disposed, channel, bore, passage or opening 26 which communicates at one end with a horizontally disposed counter-bore providing a socket 26', the latter having its mouth at one side edge of body portion 25. 85

That end of the body portion 25, opposite the end provided with the opening 26 is rabbed as at 27 to provide a shoulder 28. The length of the body portion 25 is greater and its width is less than the length and width respectively of the opening 22. The body portion 25 on that side edge opposite the side edge provided with the socket 26' is formed with an oppositely disposed socket 29 opening outwardly. The body portion 25 intermediate its end is also provided with a fingerhole 30 and an aperture 31 spaced from each other. 90 The body portion 25 is slidably mounted on the hinge rod 17 and abutment 19. The socket 26' opposes the socket 24. The socket 29 is adapted to receive the latch 18. The aperture 31 is provided for connecting a seal to the top of the coop and to the door. The opening 30 facilitates the shifting of the door from latched position on the hinge rod and abutment. 100

The door has associated therewith a coiled 110 controlling spring 32 which is mounted on the hinge rod 17 and has its end portions mounted in the sockets 24, 26'. The diameter of each of the sockets 24, 26' is such as to snugly fit the end portions of the spring 32. The tendency of the spring 32 is to maintain 115 the door in abutting engagement with respect to the latch 18 when the latter is in the socket 29. The spring 32 also acts to maintain the door against the bar 6 when the door is out of engagement with the latch 18, under such conditions the spring 32 functions to permanently maintain the door in closed position with respect to the opening 22, and also prevents the free shifting of the door on the hinge rod. The providing of the bar 5 and the door 25 with the sockets 24, 26' respectively enables for the employment of a coiled spring of greater length than the springs heretofore used for this purpose, whereby a 120 125 130

spring of greater strength can be utilized for the purpose of normally tending to maintain the door in closed position, whether the door be latched to or released from its latching means. An advantage of the employment of the socket 26' is that the base of the latter maintains the end of the coiled spring 32 at all times clear of the inner end of opening 26, thus making it unnecessary to use a metal washer to prevent the point or end of spring 32 from entering the opening 26 at the inner end of the latter, which otherwise would cause the door to jamb on its hinge rod.

The coop further includes a bottom frame 32' of the same contour and size as the top frame and the end and side frame members of the frame 32' are provided with vertically disposed sockets 33 opening at the upper face of such frame members and arranged in alignment with the vertical sockets, formed in the frame members of the top frame. Each corner of the bottom frame is provided with a vertical socket 34 which aligns with a corner opening 13'.

The coop is formed with slatted sides, each side consisting of a series of spaced slats and with each slat in the form of a cylindrical rod. The slats forming the sides of the coop are indicated at 35. Each end of the coop is slatted and formed from a series of spaced slats each in the form of a cylindrical rod and the end slats are indicated at 36. Each side slat and each end slat has its upper portion seated in a groove formed in the top slats. See Figure 5.

The extending of the side and end slats in the grooves in the top slats anchor the slats together within the frame members of the top frame. The side and end slats extend into the vertical sockets of the side and end members of the top frame and into the vertical sockets 33 in the bottom frame. Extending through the openings 13' and engaging in the sockets 34 are corner rods or tie bars 37 provided at the upper ends thereof with heads 38. The corner rods or tie bars 37 also pass through apertures formed in the body portions of corner braces to be presently referred to.

A reinforcing brace is provided for each corner of the top frame and also for each corner of the bottom frame. The corner braces for the top frame are illustrated as oppositely disposed with respect to the corner braces for the bottom frame, but it is to be understood that the top and bottom corner braces can be arranged in a like manner. As shown, by way of example the corner braces for the top frame are secured to the lower face of the latter and the corner braces for the bottom frame are secured to the upper face of the latter. As the corner braces are of like construction, but one will be described as the description of one will apply to the other.

Each corner brace is formed from a rectangular piece of sheet metal and comprises an apertured triangular shaped body portion 39, a pair of oppositely disposed, spaced arms 40, 41 which extend at an angle from the outer sides of the body portion 39 and an inturned, triangular shaped flange 42 at the outer end of each arm. The flange 42 is apertured for the passage of a holdfast device 43 to secure the flanges to the frames. The braces for the top frame member have the flanges 42 thereof secured to the lower face of the frame and the braces for the bottom frame have the flanges thereof secured to the upper face of said frame. The arms 40, 41 incline in opposite directions with respect to each other and each is provided with an aperture for the passage of a holdfast device 41' to secure the arm to a frame. Each brace has the arms thereof positioned against a side and an end member of a frame.

Secured to the lower face of the frame 32' is the bottom 44 of the crate. As illustrated by way of example the body portion of the lower corner braces are arranged against the corners of the bottom 44, but it is to be understood that such body portion can be positioned upon the upper face of the lower frame. Preferably the bottom 44 has its edges flush with the outer side faces of the frame members of the lower frame 32'.

As the corner rods or die bars extend through the body portions of the corner braces when a corner rod receives a blow for any cause, the corner brace takes care of the resistance directly thus offering the fullest protection for the wood.

In the modified form shown in Figure 6 the change resides in providing the door 46 at one corner of its hinged end with a cutout 47 providing an abutment 48 for one end of the spring 32. Intermediate the hinged end of the door the latter is formed with a cutout portion 49 providing a recess 50 and which enables for the insertion of the finger for the purpose of shifting the door, and said cutout portion 49 further eliminates any tendency for the door to bind on the hinge rod should the door become warped. The hinged end of door 46 is formed with a pair of spaced, horizontally disposed, aligning bores, channels or openings 51, 52 for mounting the door on hinge rod 17. The openings 51, 52 are spaced by the recess 50. Otherwise than that as stated the construction shown in Figure 6 is the same as that shown in Figure 1.

The main advantage in the employment of the sockets 24 and 26 is to allow the door 25 to shift on the hinge rod the full width of the space between the door and bar 5 thus allowing the latch 18 to be longer than would be possible without the use of sockets 24 and 26 where a coil spring is used for holding the door in latch position. This is a particular advantage in coops where the spacing be-

tween the slats in the top must be close to prevent chickens from putting their heads through, which according to shipping regulations must not exceed 1". The latch 18 5 should be about $\frac{3}{4}$ " to $\frac{7}{8}$ " long to prevent accidental opening while the coops are being handled.

It is thought the many advantages of a coop in accordance with this invention and 10 for the purpose set forth can be readily understood, and although the preferred embodiment of the invention is as illustrated and described, yet it is to be understood that changes in the details of construction can be 15 had which fall within the scope of the invention as claimed.

What I claim is:

1. In coop construction, a wall provided 20 with a door opening, a slidably and pivotally mounted door for partly closing said opening, one of the side walls of said opening formed with a transverse socket opening at the inner face thereof, said door formed with a bore and a counter-bore extending trans- 25 versely thereof, said counter-bore opening at one end at one side edge of the door and opposing said socket, said bore opening at its inner end in the other end of the counter-bore and at its outer end at the other side edge 30 of the door, one of the end walls of said door opening extending through said socket, counter-bore and bore and providing a pivot for the door, a controlling spring for normally spacing the door from that side wall of 35 the door opening provided with the socket, and said spring encompassing said end wall and of a length to permanently have an end terminal portion seating against the inner end of the socket and the inner end of the 40 counter-bore, the diameter of the socket and the counter-bore being such to snugly fit the spring.

2. In coop construction, a door provided 45 in proximity to one end thereof with a trans- verse bore and a transverse counter-bore, the former opening at its inner end into the inner end of the latter, said counter-bore opening at one side edge and said bore opening at the other side edge of the door, said counter-bore 50 and bore providing for the passage of a rod to hinge the door in position, and said counter-bore providing a socket for the re- ception and of a diameter to snugly fit an 55 end terminal portion of a controlling spring for the door.

In testimony whereof, I affix my signature hereto.

OSE F. CARPENTER.
